UNITED STATES PATENT OFFICE.

BENJAMIN P. FORTIN, OF HARTFORD, CONNECTICUT, ASSIGNOR TO UNDERWOOD
TYPEWRITER COMPANY, OF NEW YORK, N. Y., A CORPORATION OF DELAWARE.

TYPEWRITER CABINET.

1,404,843.

Specification of Letters Patent. Patented Jan. 31, 1922.

Application filed December 3, 1919. Serial No. 342,204.

To all whom it may concern:

Be it known that I, BENJAMIN P. FORTIN, a citizen of the United States, residing in Hartford, in the county of Hartford and 5 State of Connecticut, have invented certain new and useful Improvements in Typewriter Cabinets, of which the following is a specification.

This invention relates to improvements in 10 noise-deadening casings or enclosures for typewriters or similar machines, which, in their normal operation, produce sufficient noise to be a source of objection. As herein disclosed, it comprises a noise-insulating 15 casing to enclose the noise-producing parts of the machine while leaving the keys and other operating members accessible to the operative. A sound-deadening pad or mat is also provided to insulate the machine 20 from the table or support upon which it rests. The enclosure may be provided with openings through which work-sheets, or other material, to be typed or otherwise operated upon by the enclosed machine, may 25 be inserted, and by means of which the margin stops and other parts of the same may be adjusted, and such openings may be provided with sound-proof doors normally closing the same.

30 As herein disclosed, the invention includes a truck mounted upon the upper outside surface of the casing for movement in a direction parallel to that of the letter-spacing carriage of the typewriter. This truck is connected by means of a flexible band, 35 passing over pulleys secured to the casing, to the usual line-spacing and carriage-return lever of the typewriter. The truck is provided with a finger-piece by which it 40 may be moved, and the connection is such that a movement of the finger-piece from left to right will cause a line-spacing of the platen and a return movement of the letter-spacing carriage. This attachment 45 has the marked advantage that it will not be likely to confuse the operative, since the line-spacing of the platen and return of the letter-spacing carriage is accomplished by a movement of the aforesaid finger-piece 50 which is in no sense different from the movement of the usual typewriter line-spacing and carriage-return lever for the same purpose.

55 As herein disclosed, there are provided two transparent panels or windows, one at

the top of the machine and one at the front. By such an arrangement, light is readily admitted through the upper window for the purpose of illuminating parts of the enclosed machine, such as the letter-spacing 60 scale and the index, as well as the typed portion of the work-sheet. The window at the front serves as a means for observing the parts which are illuminated by the upper window.

65 There may also be provided a paper-guide or deflector, which may be attached to the inner upper surface of the casing, and have such form as to cause the typed end of the work-sheet to be moved rearwardly as it 70 leaves the platen, and thus prevent it from falling forward so as to intercept the line of vision between the window in the front of the casing and the printing line. This guide or deflector may be secured to the rear 75 portion of the door at the top of the casing, provided for the purpose of rendering access to the machine and for the insertion of work-sheets. The guide or deflector, when so placed, may also serve as a means 80 for guiding the leading end of the typed work-sheet to a position facilitating its removal from the machine through said door when the typing has been completed.

85 Other features and advantages will hereinafter appear.

In the accompanying drawings,

Figure 1 is a perspective view of a typewriter with my improved sound-deadening 90 casing applied thereto.

Figure 2 is a section of the same from front to rear, the typewriting machine being indicated in broken lines. In this view, doors through which access may be had to the enclosed machine are indicated in their 95 open positions by dot-and-dash lines.

Figure 3 is a perspective view of portions of the typewriter and its casing, illustrated in Figure 1, but viewed from a different angle, parts being broken away for the sake of 100 clearness.

As herein disclosed, the typewriting machine, designated generally by the reference character 1, is illustrated as being supported upon a sound-deadening pad or mat 2, to 105 insulate the same from the table, desk or other supporting surface 3 upon which the machine rests. Enclosing the typewriter is a casing 4, which may be of sheet-metal or other appropriate material, and which may 110

likewise rest upon the sound-deadening pad 2. An opening is provided in the casing 4 through which may protrude the front portion of the typewriter, including the number 5 and alphabet keys 5, by which is operated the mechanism through which types 6 are moved to the printing point of a platen 7. Openings are also provided through which may protrude the line-lock-release key 8 and 10 the bichrome-ribbon-shift key 9.

For the purpose of rendering the aforesaid casing 4 sound-proof, it may be provided with a lining 10 of felt or other sound-insulating material. This casing, which has 15 an open bottom for convenience in assembling and disassembling it relatively to the typewriter may rest upon the pad 2 clear of the machine frame, and may be provided with overhanging extending portions 11 to 20 provide for the endwise travel of the usual letter-spacing carriage 12 in which is mounted the platen 7 of the typewriter. The body of the casing may set down in the well usually provided in the typewriter desk, and 25 these portions 11 may extend above the top of the desk.

To provide for the return of the typewriter carriage after it has reached the end of a line, in the course of typing a work-sheet, there is provided a finger-piece 13 mounted on a truck 14 and connected with the usual line-spacing and carriage-return lever 16 by means of a flexible band or strip 17. The line-spacing lever 16 is provided with the usual arm 18 for bringing a pawl 19 into engagement with a ratchet-wheel 20, so as to impart a line-spacing rotation to the platen at each movement of the line-spacing lever 16.

40 The truck 14, carrying finger-piece 13, is mounted on rollers 21 adapted for movement in the same direction as the typewriter carriage in channels 22 in a track-bar or guide-way 23 secured by means of supports 24 to the exterior upper surface of the casing 4. Stop pins 25 are provided to limit the movement of the truck 14 to the right and left, respectively. One end of the flexible band or strip 17 is attached at 26 to the truck 14. 45 From this point, the band passes over a pulley 27 mounted on the outside of the casing 4 at the left end thereof. After passing over this pulley 27, the band 17 passes through a slot 28 in the casing, thence across to the 50 other end of the casing and over a pulley 29 mounted within the same. From the pulley 29, the band 17 is carried to the line-spacing and carriage-return lever 16 to which it may be connected by a loop 30, so 55 as to be readily attachable and detachable at will. Said finger-piece 13 projects at the front of the casing in position to be grasped by the operator, and is connected, as explained, to effect both a line-spacing operation and the return of the carriage, and trav-

els in the same direction as the carriage and to the same extent.

To provide for the insertion of worksheets or other material to be typed or worked upon by the enclosed machine, without removing the casing 4, there may be provided an opening 31 normally closed by a door 32 hinged at 33, and having a knob 34, so as to be readily swung from its closed position, as indicated in full lines in Figure 2, 75 to its open position, as indicated in dot-and-dash lines in the same figure. To prevent the leakage of sound between the door and the adjacent portions of the casing, the margins of the door may be provided with strips of 80 soft rubber 36. The door itself may be lined with felt or sound-deadening material 37, similar to the lining of the body of the casing.

To provide for the setting of the margin 85 stops 38 of the typewriter, there may be provided a second opening 39 normally closed by a door 40 of a construction similar to the door 32. This door 40 may be normally held in its closed position by retaining 90 springs 41, and may be provided with a knob 42 to facilitate the opening and closing thereof.

Both of the doors 32 and 40 may be provided with transparent panels or windows 95 43, the window in the door 32 being for the purpose of admitting light to illuminate parts of the enclosed machine, such as the letter-scale and its index as well as the typed portion of the work-sheet above the printing 100 line. The window in the door 40 provides means for observing the above-mentioned parts, thus illuminated by the window in the door 32. These two windows thus co-operate to permit constant inspection of the subject-matter being typed upon the work-sheet 105 without opening the doors or removing the casing from the machine.

To prevent the work-sheet 44 from turning forward, as it is being typed, so as to fall between the window 43 and the printing line, and thus prevent the observation of the portion of the sheet being typed, there may be provided a deflector or paper-guide 45. This deflector may conveniently be attached 110 to the inner side of the door 32 at a point near the rear thereof, and said deflector may be curved forwardly and downwardly in a form such as to guide the typed part of the work-sheet upwardly and rearwardly in a 115 direction away from the window 43. This guide is also effective to retain the typed end of the work-sheet in a position convenient for the removal of the sheet from the machine on opening the door 32.

In order that the casing 4 may be readily applied to, or removed from, the machine, the bichrome-ribbon-shift key 9 may be detachably secured to its shaft 46 by means of a set-screw 47, so that the shaft may be 120

thrust through an opening in the casing 4 and the keys subsequently secured to the shaft by means of the set-screw. In like manner, the lock-release key 8 may be passed 5 through an opening 48 in the casing 4.

Variations may be resorted to within the scope of the invention, and portions of the improvements may be used without others.

Having thus described my invention, I 10 claim:

1. The combination with a typewriting machine having a letter-spacing carriage and a line-spacing and carriage-return lever therefor, of a noise-deadening casing or enclosure 15 for the noise-producing portion of said machine, and a carriage-return and line-spacing attachment therefor, comprising a finger-piece mounted for movement along the upper part of said casing in 20 a direction parallel with the movement of the type-writer carriage, and a movement-transmitting connection from said finger-piece to the line-spacing and carriage-return lever of said typewriter.

2. The combination with a typewriting machine having a letter-spacing carriage and a line-spacing and carriage-return lever therefor, of a noise-deadening casing or enclosure 25 for the noise-producing portion of said machine, and a carriage-return and line-spacing attachment therefor, comprising a truck movable along a track mounted on the outside of said casing, a finger-piece by which said truck may be moved, and means, 30 including a flexible connection and pulleys, for transmitting motion from said truck to the line-spacing and carriage-return lever of said typewriting machine.

3. The combination with a typewriting 40 machine having a letter-spacing carriage and a line-spacing and carriage-return lever therefor, of a noise-deadening casing or enclosure for the noise-producing portion of said machine, and a carriage-return and 45 line-spacing attachment therefor, comprising a truck movable along a track mounted on the outside of said casing, a finger-piece by which said truck may be moved, and means, including a flexible connection and 50 pulleys, for transmitting motion from said truck to the line-spacing and carriage-return lever of said typewriting machine, one of said pulleys being mounted at one end of said casing on the outside, and the other at 55 the other end of said casing on the inside, said flexible connection passing from said truck over the outside pulley, thence into the casing, thence over the inside pulley, and

thence to the line-spacing and carriage-return lever.

4. A noise-deadening casing or enclosure 60 for a typewriting machine, said casing having a hinged door through which a work-sheet may be inserted in readiness to be typed, said door having a paper-guide or deflector attached to its under side to direct the typed end of the work-sheet upwardly and rearwardly from the platen.

5. A noise-deadening casing or enclosure 70 for a typewriter having a window conveniently located for the observance of the subject-matter typed on a work-sheet by an enclosed machine, said casing having a paper-guide or deflector projecting from its inner upper surface to direct the typed end 75 of said work-sheet upwardly and rearwardly from the platen, so as to prevent it from passing between said printing line and said window.

6. The combination with a typewriting 80 machine having a letter-spacing carriage and a platen, of a noise-deadening casing for the body of said machine, and a handle projecting at the front of the casing and connected to effect both a line-spacing operation and the return of the carriage, said handle traveling along a closed portion of the casing in the same direction as the carriage.

7. A noise-deadening casing for a typewriter 90 machine, having an extensive opening in the front through which the typewriter keyboard protudes, and having overhanging extending portions at the sides to provide spaces for the endwise travel of 95 the carriage, and a handle projecting at the front of the casing and movable along one of said overhanging portions and traveling in the same direction as the carriage to effect both a line-spacing operation and the 100 return of the carriage.

8. A sound-deadening typewriter assemblage comprising a sound-deadening mat upon which the typewriter stands, and a sound-deadening casing surrounding the 105 typewriting machine and also standing upon said mat, said casing having an open bottom for convenience in assembling and disassembling the casing relatively to the typewriting machine, and said casing also 110 having an extensive front opening through which protrudes the typewriter keyboard.

BENJAMIN P. FORTIN.
